UNITED STATES PATENT OFFICE.

PALUEL J. FLAGG, OF FLUSHING, NEW YORK.

METHOD AND APPARATUS FOR DETERMINING THE AMOUNT OF OXYGEN COMBINED WITH THE HÆMOGLOBIN OF BLOOD.

Application filed January 17, 1922. Serial No. 530,008.

To all whom it may concern:

Be it known that I, PALUEL J. FLAGG, a citizen of the United States, residing at Flushing, county of Queens, State of New

5 York, have invented certain new and useful Improvements in Methods and Apparatus for Determining the Amount of Oxygen Combined with the Hæmoglobin of Blood, of which the following is a specification.

10 This invention relates to a method and apparatus for determining the amount of oxygen combined with the hæmoglobin of the circulating blood.

The invention provides a clinical method 15 and apparatus whereby the amount of oxy-hæmoglobin in the circulating blood may be determined, and further provides a ready and simple method of and an apparatus for making such determination, and by which 20 approximately accurate and quick results can be obtained. The invention is hence of great utility to physicians and surgeons in their practice, and is of particular value to surgeons or their assistants in aiding them 25 to control the administration of anæsthetics during operations.

An embodiment of the apparatus of the present invention is shown in the accompanying drawings of which embodiment—

30 Figure 1 is a perspective view.

Figure 2 is a top plan view with the cover removed.

Figure 3 is a top plan view of the color scale.

35 Figure 4 is a view in cross section.

In carrying out the present invention I first prepare a series of colored cards or indices corresponding to the color of blood containing different amounts of oxyhæmo-

40 globin, these cards or indices being designated by the numerals 10, 11, 12, 13, 14, 15, 16, 17 on the accompanying drawing, and these cards or indices 10 etc. are preferably mounted consecutively on a common mount,

45 being most conveniently in the form of segments mounted or printed on a round disk 30 which is conveniently rotatably mounted on a base 31, as indicated at 32, and the series is preferably overlaid by a cover 35,

50 having a window or sight opening 38 therein, the window being preferably slightly smaller than the segmental color-cards or indices 10, etc. Between the color-card 30 and the cover 35 there is preferably ar-

55 ranged a disk 40, having portions 42^a, 40^c,

40^b of different transparency, corresponding to the various tissues or covering overlying the blood capillaries such as the mucous membrane (40^a) the finger nail (40^c), skin (40^b) and a completely transparent 60 portion (40^b, 40^a, 40^c) which may be segmental cut-out portions or openings in the said disk 40. The disk 40 is independently movable under the cover 35, so as to bring one or another of the differential transparent portions 40^a etc. into registry with the window 38 in the cover. A lug 40^b may be provided on the disk 40 for manipulating it to bring the proper transparency into place under the window 38. In the form of 70 embodiment shown, the color-disk 30 is preferably made of slightly greater diameter than cover 35 and disk 40, so that it may be readily turned to match a color-segment 10 etc. with the blood to be observed. On 75 or in conjunction with each color card 10 et seq. there is a mark or number indicating the degree of oxygen unsaturation (oxygen loss) in blood of a color corresponding to the color of that card or segment, the 80 numbers being preferably arranged in a series on a light ground, as indicated at 41, and these numbers are conveniently displayed through a separate window opening 43, simultaneously with the respective color 85 segments. The numbers in the present instance represent percentages of oxygen unsaturation (oxygen loss) and the series are arranged in multiples of ten.

In preparing the series of color cards, 90 the extremes corresponding to complete saturation of the hæmoglobin with oxygen (0) and complete cyanosis or unsaturation of the oxyhæmoglobin (100%).

The extremes of the scale are obtained 95 as follows:—

A specimen of oxalated blood is exposed to an atmosphere of pure oxygen until there is no further change in its color. The shade resulting is matched by a non-fading 100 ink of a known formula. A portion of the same specimen is then exposed to an atmosphere of pure hydrogen until there is no further change in its color. This shade is also matched.

The first specimen yields a color represented by 0 unsaturation, the second specimen yields a color represented by 100% unsaturation.

The original specimens are transported 110

under air tight conditions to the laboratory where careful quantitative determination of oxygen is made. The haemoglobin of the first specimen will be found to be saturated with oxygen. The haemoglobin of the second specimen will be found to be completely unsaturated.

Intermediate percentages are then arrived at by weight proportions of the two extremes.

After the scale is made on this basis, specimens of blood are partially unsaturated by hydrogen. The percentage of unsaturation is read by means of the scale and the actual unsaturation is quantitatively determined by the Van Slyke method. The readings of the scale and by analysis are made to co-incide. Inks of known formulæ, corresponding in color to the shade of the blood having the determined percentage of oxygen, are then used to color the different intermediate cards, and these cards preferably are arranged in series, as shown.

To make a determination of the amount of oxygen or oxyhaemoglobin in the blood, a comparison is directly made between the circulating blood of the patient and the series of color-cards 10 et seq. the percentage being directly and immediately given by the number on the card which matches the circulating blood under observation. The matching may be readily effected by turning the disk 30 bearing the color cards, and the circulating blood for the purpose of matching may be escaping from a wound or blood beneath some tissue of the body, as beneath the mucous membrane of the lips, finger-nail, skin or the like, in which latter case, the differential transparency disk 40, would be turned until a segment or part 40^a etc. corresponding to the transparency of the skin, nails, or other tissue or covering registers with the window 38.

The absorption of oxygen by the haemoglobin, resulting in oxyhaemoglobin, or the loss of oxygen by the oxyhaemoglobin resulting in haemoglobin (technically called reduced haemoglobin) as accomplished by a remarkable change in the mass color of the blood. Blood (haemoglobin) saturated with oxygen is of a brilliant brick red color. As the oxygen is gradually reduced, this shade gradually changes until with complete deoxidation, a deep mahogany color is seen.

Under normal conditions, the blood in the arteries is completely saturated with oxygen. As it passes through the capillaries into the veins it loses part of its oxygen and in doing so changes its color. The amount of this change will depend upon the duration of its exposure to the tissues in contact with the capillary walls. If the exposure is short, the change will be slight, if long, greater, up to a point where all the available oxygen will have been absorbed. Broadly speaking,

the duration of this exposure and consequent absorption will depend upon the quality of air breathed, the amount of air breathed, the condition of the heart and the condition of the blood vessels. A reduction in the normal quality or volume of the air breathed will reduce the available oxygen. Abnormalities in the heart of blood vessels will delay its transference. Therefore, abnormal conditions of the respiratory organs caused by mechanical obstruction as during the unconsciousness of anaesthesia, or by disease, as pneumonia, abnormal conditions of the heart as valvular disease, abnormal conditions of the blood vessels as in mechanical pressure, or in the capillary stasis from superficial chilling, or disease caused by chemicals, all results in varying degrees of deviation from the normal shade of the blood. A patient who suffers from a diminution of the normal oxyhaemoglobin is said to be cyanosed. Cyanosis, heretofore, has merely conveyed an indistinct general idea of blueness from loss of oxygen, technically spoken of as oxygen unsaturation. It has also been erroneously attributed to an increase in carbon dioxide. An absence of oxyhaemoglobin is incompatible with life, and any deviation from complete saturation is an indication of an abnormal condition, due to disease or mechanical embarrassment. To instruct an interne to keep his patient free from cyanosis depends upon the interne's conception of cyanosis. There has been no standard scale to instruct an interne not to allow more than 20, 30 or 40% unsaturation. To speak in terms of percentage is to speak definitely. Furthermore, it is an acknowledged fact that the constant observation of a color soon results in a loss of color perception for the particular color observed. It thus becomes essential to provide a known standard for comparison.

The most important sign in gas oxygen 110 anaesthesia is the color sign and yet, no definite measure of this color scientifically based has ever been offered. By the present instrument normality is indicated at one extreme and at the other, death.

The instrument is valuable in every operating room, to the nurse in the recovery room, to the surgeon who operates in the home, to the medical man who wishes a simple, rapid means of estimating the degree of oxygen unsaturation suffered by his pneumonia or heart cases, and to the clinician who wishes to diagnose mediastinal tumors or capillary stasis from any cause.

To the research worker it provides a simpler means of determining preliminary oxygen readings without recourse to involved methods of quantitative analysis.

It is also of value commercially to the portrait painter and may even be used in a

beauty parlor for the standardization of rouge.

It is a fundamental basic measure of the life-giving and life sustaining element of the blood, the oxyhaemoglobin.

The invention may receive other embodiments of apparatus than that herein specifically illustrated and described.

What is claimed is—

- 10 1. A method of measuring the oxyhaemoglobin content of the circulating blood by comparing the blood with a standard color scale having indicia giving the values of oxyhaemoglobin unsaturation for the various color divisions ascertained by quantitative chemical determination.
- 15 2. A method of measuring the oxyhaemoglobin content of the circulating blood by comparing the blood with a standard color scale having indicia giving the values of oxyhaemoglobin unsaturation for the various color divisions ascertained by quantitative chemical determination, and laying over said color scale a transparency corresponding to the natural tissue covering said blood.
- 20 3. An apparatus for determining the amount of oxyhaemoglobin in the circulating blood comprising a color scale having color divisions and indicia giving the amount of oxygen unsaturation in blood corresponding to the color of a division of said scale.
- 25 4. An apparatus for determining the amount of oxyhaemoglobin in the circulating blood, comprising a color scale having color divisions and indicia giving the amount of oxygen unsaturation corresponding to the color of a division of said scale, said divisions being mounted together consecutively.
- 30 5. An apparatus for determining the amount of oxyhaemoglobin in the circulating blood, comprising a color scale having color segments and indicia giving the amount of oxygen unsaturation corresponding to the color of said segments, said segments being mounted consecutively on a rotatable part.
- 35 6. An apparatus for determining the amount of oxyhaemoglobin in the circulating blood, comprising a color scale having color segments and indicia giving the amount of oxygen unsaturation corresponding to the color of said segments, said segments being mounted consecutively on a rotatable part, and a cover having a window therein for exposing one of said segments at a time.
- 40 7. An apparatus for determining the amount of oxyhaemoglobin in the circulating blood, comprising a color scale having color segments and indicia giving the amount of oxygen unsaturation corresponding to the color of said segments, said segments being mounted consecutively on a rotatable part, and a cover having a window therein for exposing one of said segments at a time, said cover having a separate window therein for exposing the indicia corresponding to the respective segments.
- 45 8. An apparatus for determining the amount of oxyhaemoglobin in the blood, comprising a color scale having color segments and indicia giving the amount of oxygen unsaturation corresponding to the color of said segments, and a part having a transparency corresponding to the tissue overlying the blood under observation, adapted to be placed over a color segment.
- 50 9. An apparatus for determining the amount of oxyhaemoglobin in the circulating blood, comprising a color scale having color segments and indicia giving the amount of oxygen unsaturation corresponding to the color of said segments, said segments being mounted consecutively on a rotatable part and a rotatable part having a series of transparencies corresponding to the transparencies of various tissues overlying the blood, adapted to be placed over said color parts.
- 55 10. An apparatus for determining the amount of oxyhaemoglobin in blood, comprising a base, a disk having a series of color segments thereon and having indicia thereon giving the amount of oxygen unsaturation in blood under observation corresponding to the color of said color segments, a disk having a differential transparency corresponding to the transparency of various tissues overlying the blood, adapted to overlie said color-scale and a cover having a window through which said one or another of said color segments is to be seen.

In testimony whereof, I have signed my name to this specification in the presence of two subscribing witnesses, this 11th day of January 1922.
